UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

DEVELOPING APPARATUS

Application filed December 22, 1927. Serial No. 241,780.

This invention relates to a developing apparatus for light sensitive paper and particularly to an apparatus for developing the paper by means of the fumes of a developing gas.

One of the objects of my invention is to provide a developing apparatus adapted to contain a material such as a liquid, and to house a sheet or roll of the paper to be developed preferably above the developing liquid so that the gases from the liquid will rise upwardly through the folds of the paper to develop the same, and this construction includes a cover for the liquid containing chamber which cover is adapted to be opened and closed by a control member operable from the exterior of the device so that the cover can be manipulated without the removal of the housing, which construction prevents the escape of the developing fumes when the cover is opened or closed.

Still another object of my invention resides in providing a simple type of developing apparatus which includes a base for containing the developing liquid and from which rises an enclosing housing or tower adapted to receive a sheet or coil of the paper to be developed and wherein the liquid containing member of the base is provided with a cover for opening and closing the liquid containing receptacle and provided with a cover handle for opening and closing the cover whereby to permit the escape of the developing fumes into the tower or to shut off the escape of the fumes.

Still another object of my invention resides in the means of supporting the roll or sheet of paper to be developed immediately above the container for the developing liquid as for instance by means of a wire or a foraminated support located above the shiftable cover so that the cover may be opened or closed without contacting with the paper, or alternatively, the paper may be supported directly upon the movable cover.

Still a further object of my invention resides in providing a construction wherein the cover member is directly operable by means of the tower which encloses the paper to be developed, as for instance by means of a con-

struction wherein the tower may be shifted angularly or longitudinally to open or close the cover member.

Still another object of my invention resides in providing an alternative construction wherein in order to open the closure for the liquid container, the tube or tower must be first removed and then the closure may be manually opened, and this construction also includes means for retaining the cover in tightly closed position.

Still further objects of my invention reside in providing the various types of control means for opening and closing the cover either by the actuation of the tubular tower, or by the actuation of a control member such as the wheel or the lever of the cam member located on the exterior of the developing apparatus so that the tube need not be removed for the opening and closing of the cover, or by means of a simple type of hand operated device on the cover itself, which device is operable after the tubular tower has been removed, for opening and closing the cover.

These and other objects of my invention will be apparent from a perusal of the following specification when taken in connection with the accompanying drawings wherein:

Fig. 1 is a view of one form of my device wherein the cover member is opened and closed by means of a hand wheel located at the base of the developing apparatus;

Fig. 2 is an exterior view of the device, the upper portion of the paper tube or housing being shown in section;

Fig. 3 is a sectional view taken through Fig. 1;

Fig. 4 is another modification showing the manner of opening and closing the cover by means of an axial pin through the container member and the loosely pivoted lever for operating the same;

Fig. 5 is a top plane view of the same;

Fig. 6 is yet another modification of the use of a lever and a cam for raising and lowering the cover;

Fig. 7 is a section on line 11—11 of Fig. 6;

Fig. 8 is a section corresponding to Fig. 6 but taken at right angles thereto.

Referring now to the drawings in detail,

my invention comprises a suitable base having a well or liquid reservoir to receive the usual developing liquid such as ammonia. This base is provided with a cover for the well which is adapted to raise and lower so as to permit the gaseous fumes to rise or, alternately, to wholly enclose the gaseous fumes so they cannot escape. In addition the base is adapted to receive a relatively long tube or tower comprising a housing in which the light sensitive material to be developed may be supported, preferably as in a roll, and in a manner so that the gaseous fumes arising from the well will pass upwardly into the end of the tube, the top of which is closed, so that the light-sensitive paper therein will be developed. In the several arrangements of my invention the tube and the cover for the reservoir in the base are arranged so that the cover for the reservoir may be opened or closed, or may be retained in closed position without opening so that the possibility of fumes escaping from the reservoir when the tube or tower is removed with the developed paper therein is eliminated.

In the construction shown in Figures 1 to 3, inclusive, the opening and closing of the cover for the tube is accomplished by means of an operative connection extending to a point outside of the developing chamber so that the fumes are unable to escape during the opening and closing of the cover. In this instance the casting 72 is formed with a concentric and axially located sleeve 74 to provide a concentric ring-like container 76 in which the developing fluid is held. The inner bore of this sleeve 74 is threaded to receive a spindle 78 likewise threaded and provided on its lower end with a hand wheel 80 and on its upper end with a circular cover 82 which is riveted, as at 84, to the spindle 78. The upper edge of the casting 72 is preferably provided with a beveled seat, although this is not absolutely essential, and this beveled seat is adapted to co-operate with a similar beveled seat 86 on the under surface of the circular cover 82. In addition, this circular cover 82 is provided with an upstanding flange 88 which provides a pocket or support for the sheet or roll 90 of light sensitive material to be developed. It will be noted in this instance that this material is supported directly on the top of the cover and that when the hand wheel 80 is turned, the cover 82 will be opened or closed while at the same time supporting the material. The fumes will rise and pass upwardly at the peripheral edges of the cover 82. In this instance also, no escape of the developing fumes can occur during the opening and closing of the cover. In this form of device I provide a drain and filling opening 92 at the base of the receptacle 76 which consists of a plug threading into an

aperture in the base of the casting 72 and this plug is provided with a drain outlet 94 and a filling inlet 96 both of which are controlled by a valve 98 which, when in one position, opens and closes the filling inlet and when in a still further outward position, opens and closes the drain.

Another important feature of this form of my invention resides in the construction of the base for supporting the casting 72 and the tower. In this construction the basal support consists of a bracket 73 having a vertical portion more or less in the form of a V the apex of which is formed with a horizontal extending toe and just above this apex the wall portion is provided with apertures for the reception of a screw. The horizontal portion 73 in the bracket is arranged so as to support the casting 72. By means of screws 75 passing through perforated ears 77 on the base of the casting and likewise passing through threaded openings in the horizontal wall 73 of the bracket. Two of the ears and the screw passing thereto are adapted to detachably assemble the legs 79 so that when the apparatus is adapted to be stood on the floor or other horizontal support, the bracket will constitute one leg and the other two legs will be melted into place on the ears and held in place by means of the screws 75 whereas when it is desired to mount the developed apparatus on a wall or panel, the legs 79 are detached and screws are passed through the openings 81 of the bracket so that the bracket may be screwed upon the wall. The foregoing apparatus provides a very convenient mounting for my improved developing apparatus.

It will be noted that this horizontal portion 73' of the bracket is considerably apertured to permit the passage of the operating spindle 78. This is preferably accomplished by forming the base with the horizontal ribs 81 which are spaced apart.

From the foregoing it will be appreciated that I have provided a very ingenious and advantageous construction for the development of the sensitive paper by means of developing gasses; that this structure, by reason of its compactness and particularly by reason of the improved means for closing the cover, eliminates the objectionable features of existing devices; that is, the escape of the obnoxious fumes into the atmosphere when the tube is inserted and removed.

In the construction shown in Figures 4 and 5, the base 100 is provided with a central axially disposed sleeve 102 bored to receive a pin 104 which is adapted to slide vertically in the sleeve. The portion 106 of the base immediately surrounding the sleeve provides the receptacle for the developing liquid. The pin 104 is or may be fastened to the cover 108 which cover, when in normally closed position, engages at its edges in a seat 110 in the

upper edge of the casting 100, which edge is formed with a beveled lip forming a substantially gas tight joint with the corresponding beveled edge of the cover. Figure 4 shows the cover in open position. Means for raising and lowering the pin 104 is provided pivoted on the under side of the base 100 which means, in the present instance, consist of a lever 110 pivoted intermediate its length on a swivel 112 so that by moving the lever about its pivot, the pin 104 is shifted axially in order to raise the cover 108. The lever may be arranged for pivotal movement in any desired plane, and I have shown in Figures 4 and 5, the lever 110 pivoted to swing in planes, one of which is transverse to the other. The first plane of pivot is in a vertical direction as shown in Fig. 4, while the second plane of pivot is clearly shown as in the horizontal plane in Fig. 5. This construction permits the lever to be shifted to the right or left to co-operate or disconnect from a depending finger 114 fastened to the basal edge of the tubular cover 116. Obviously, this finger 114 may be located on the base, if desired. However, by placing it upon the tube 116, the raising and lowering of the cover 108, when the tube 116 is applied or removed from the base 100, is automatically controlled. On the other hand, by shifting the lever 110 in a horizontal plane it may be moved out of the vertical plane of finger 114. This construction may be used either automatically to open the cover 108 or may be operated by hand, as for instance, by pressing downwardly on the outer end of the lever 110, the cover may be opened and then by shifting the lever laterally it may be placed under the lower end of the finger 114 so that the cover is held in raised position. Obviously, by merely turning the tube 116, the finger will be removed from over the top of this lever 110 and the cover will drop by gravity.

In the modification shown in Fig. 7 to 9 inclusive, I provide still another means for opening and closing the cover from the exterior of the developing chamber. In this case the base 118 is likewise provided with an axial sleeve 120 bored to receive a pin 122 which is adapted to slide up and down in this sleeve 120. This pin has rigidly connected to its top portions the cover 124 adapted to open and close upon the lip of the casting 118 which forms the usual developing liquid chamber. In order to raise and lower the pin 122, I provide the under surface of the casting 118 with a depending projection to which is pivotally mounted, as at 126, the operating lever 128. The inner end of this lever is provided with an arcuately shaped cam member 130, the upper face of which is substantially wedge shaped as shown at 132, and this portion is adapted to co-operate with the basal portion 134 of the stem 122 which basal portion has a depending portion 136 of smaller diameter

which passes through the slot in the arcuate link whereby to form a guide. The upper portion 134 of the stem 122 being larger than the extending slot, will not pass therethrough, and the base of this portion 134 is preferably rounded so as to slide freely along the upper cam surface of the arcuate slotted link. Hence, when the outer end of the lever 128 is moved in one direction or the other, the pin 122 and cover will be raised or lowered without the removal of the developing tube 138.

It will thus be appreciated that by reason of the foregoing constructions involving a detachable tube or tower and a base portion forming a receptacle for the developing liquid and provided with a cover to permit communication of the fumes rising from the developing liquid into the tower or absolutely cutting them off, and in further providing either for the automatic opening and closing of this cover either from the shifting of the tube itself or from shiftable cover operating mechanisms extending to the outside of the developing chamber, I am enabled to prevent the escape of the developing fumes during the opening and closing of the cover. While in certain of the other forms I provide most simple and yet effective constructions for opening and closing the cover but without the features of accomplishing it either by the shifting of the tube on the base or without the exterior control. In these latter instances the cover is opened or closed by removing the tube and by positively operating the cover.

It will also be appreciated that by reason of the novel construction of the paper support or bracket, I am enabled to permanently mount this bracket on the base so that it does not constitute a part which may be lost during the operation of my device, and further that by reason of the novel construction of this paper bracket I am enabled not only to have it project well up into the tower or tube where it may support the paper in the gaseous zone in the tube, bearing in mind that this gas arises to the upper end of the closed tube, but I am also able to support the paper in a manner such that the support does not interfere with the opening and closing of the reservoir. The construction of the cover 128 and the manner of pivotally mounting it upon the walls forming the well is also a most advantageous construction, since this cover is thus arranged to open substantially to full position and thereby permit the quick escape of the gaseous fumes from the well; in addition this construction provides an effective seal for the top of the well when the cover is closed, yet at the same time permits the positioning of the vertical legs 68 of the bracket 126 on the walls of the well.

Having thus described my invention what I claim as new and desire to secure by Letters Patent is:

1. In a developing apparatus, the combina- 130

tion of a base forming a receptacle for a developing medium, a tubular tower detachably connected to said base and adapted to receive a sheet of light-sensitive material to be developed by fumes evolved by the developing medium, a cover for opening and closing the receptacle, a pin shiftably mounted in the base and operatively engaging said cover to shift the same, a lever pivotally mounted on said base and adapted to be operated from a point on the exterior of the base for shifting the pin, the lever being mounted for operative movement in a plane transverse to the operating movement of the pin and co-operating means for engaging the lever when the latter is shifted in its transverse plane for holding the cover in raised position.

2. In a device of the class described, the combination of a base formed with a receptacle for a developing medium, a tubular tower detachably engaging the base and providing a developing chamber, a cover for the receptacle, a pin slidably mounted in the base and operatively engaging the cover, a lever pivoted on said base intermediate its ends and having one end arranged to engage the pin and a locking finger adapted to engage the other end of the lever when in one of its shifted positions, so as to hold the cover in open position.

3. In a developing apparatus, the combination of a base having a receptacle for a developing medium, a tubular tower detachably mounted on the base and communicating with the receptacle to form a developing chamber, a cover for the receptacle, a pin slidably mounted on the base and operatively engaging the cover to raise the same, a lever pivoted on the base intermediate its end and having its inner end engage the base of the pin, a depending finger connected to the tubular tower and adapted to engage the outer end of the lever.

4. In a developing apparatus, the combination of a base having a receptacle for a developing medium, a tubular tower detachably mounted on the base and communicating with the receptacle to form a developing chamber, a cover for the receptacle, a pin slidably mounted on the base and operatively engaging the cover to raise the same, a lever pivoted on the base intermediate its end and having its inner end engage the base of the pin, a depending finger connected to the tubular tower and adapted to engage the outer end of the lever, said lever being pivoted so as to be shiftable in both vertical and horizontal planes.

5. In a device of the class described, the combination of a base forming a receptacle for a developing medium, a tubular tower detachably mounted on said base and communicating with the receptacle and forming a developing chamber, a cover adapted to open and close said receptacle, means for shifting

said cover with respect to the base, said cover forming a support for the sheet of light-sensitive material to be developed by the fumes of the liquid in said receptacle.

6. In a device of the class described, the combination of a base forming a receptacle for a developing medium, a housing removably mounted to the base and communicating with the receptacle and adapted to receive a sheet of light sensitive material to be developed by the fumes of the developing medium, a closure for the receptacle and means extending through the walls of the receptacle for opening the closure. 70

7. In a device of the class described, the combination of a base forming a receptacle for a developing medium, a housing removably mounted to the base and communicating with the receptacle and adapted to receive a sheet of light sensitive material to be developed by the fumes of the developing medium, a closure for the receptacle and means extending through the bottom of the receptacle for opening the closure. 80

8. In a device of the class described, the combination of a base forming a receptacle for a developing medium, a housing removably mounted to the base and communicating with the receptacle and adapted to receive a sheet of light sensitive material to be developed by the fumes of the developing medium, a closure for the receptacle and means including an axially movable shaft extending through the bottom of the receptacle for opening the closure. 95

9. In a device of the class described, the combination of a base forming a receptacle for a developing medium, a housing, adapted to receive light sensitive material to be developed by fumes of the developing medium, removably mounted upon the base and communicating with the receptacle, a closure for said receptacle normally arranged to seal the receptacle against the escape of fumes and axially movable means for shifting the closure from sealing position. 100

10. In a device of the class described, the combination of a base forming a receptacle for a developing medium, a housing adapted to receive light sensitive material to be developed by fumes of the developing medium, removably mounted upon the base and communicating with the receptacle, a cover for said receptacle normally arranged to seal the receptacle against the escape of fumes, and axially movable means extending through the walls of the receptacle whereby to raise the cover to thereby permit of the escape of developing fumes into the housing. 115

11. In a device of the class described, the combination of a base forming a receptacle for a developing medium, a housing, adapted to receive light sensitive material to be developed by fumes of the developing medium, removably mounted upon the base and com- 125

16. A developing apparatus for light sensitive material comprising a compartment having an opening for the insertion of light sensitive material into the compartment, means for creating chemically active gases and projecting them into the compartment through the opening thereof and manually operable means for controlling the projection of said gases into said compartment. 70
17. A developing apparatus comprising means forming a developing chamber having an opening, a separable closure for said opening, means formed and arranged in said closure for emitting developing gases into the chamber and manually operable means for controlling the emission of said gases into 80 said chamber. 75
18. A developing apparatus comprising means forming a developing chamber having an opening, a separable closure for said opening, means formed and arranged in said closure for emitting developing gases into the chamber and means including a shiftable member extending through said closure for controlling the emission of said gases into 90 said chamber. 85
19. A developing apparatus comprising means arranged to form a developing chamber having an opening, a separable closure for sealing said opening, said closure being formed with a receptacle for a developing medium, means for closing said receptacle whereby to prevent the escape therefrom of the developing medium and means for opening said receptacle whereby to permit of the 100 emission of gases into the developing compartment. 95
20. A developing apparatus comprising means arranged to form a developing chamber having an opening, a separable closure for sealing said opening, said closure being formed with a receptacle for a developing medium, means for closing said receptacle whereby to prevent the escape therefrom of the developing medium, said means comprising a cover for the receptacle and means operable from outside of the closure for shifting the cover. 113
21. A developing apparatus comprising means arranged to form a developing chamber having an opening, a separable closure for sealing said opening, said closure being formed with a receptacle for a developing medium, means for closing said receptacle whereby to prevent the escape therefrom of the developing medium, said means comprising a cover for the receptacle, and an axially shiftable member co-operating with said cover and operable from the exterior of said closure for shifting the cover to open the 120 receptacle whereby the developing medium may be emitted into the chamber. 115
